[57] CLAIM

The ornamental design for a balloon spreader, as shown and described.

DESCRIPTION

FIG. 1 is a perspective view of a balloon spreader showing my new design in use;

FIG. 2 is a front view thereof;

FIG. 3 is a back view thereof;

FIG. 4 is a top view thereof;

FIG. 5 is a side elevational view; and,

FIG. 6 is a bottom view thereof.

The balloons shown in broken lines in FIG. 1 denote the nature and environmental use of the design and are not part of the design.
